RANSOM W. DAVENPORT, OF DETROIT, MICHIGAN, ASSIGNOR TO CHICAGO PNEUMATIC
TOOL COMPANY, OF NEW YORK, N. Y., A CORPORATION OF NEW JERSEY

REFRIGERATING APPARATUS

Application filed January 18, 1927. Serial No. 161,730.

This invention relates to the art of producing refrigerating effects artificially with particular reference to systems operating on the conventional or Rankine cycle. It comprises both a process and apparatus adapted for practicing the process, and has been developed with the small domestic outfit or machine particularly in mind but its application is by no means confined thereto.

All Rankine cycle systems so far as known have been heretofore constructed and operated so as to have liquid refrigerant in both the warmer and colder parts of the system at all times, thus maintaining a high pressure in the condenser or high side of the system and a low pressure in the evaporator or low side of the system. This pressure condition results from the customary practice of storing liquid refrigerant in a condenser or receiver at room temperature and feeding it only in such amounts as will keep a constant level or amount in the evaporator. Since evaporable liquid is always present in the higher temperature part of the system, the pressure therein is always higher than in the refrigerator or evaporator. The pump or compressor must accordingly be started up against a great pressure head which is very objectionable in the case of the domestic machine which is arranged for frequent starts and stops, and where economy of operation is an important consideration.

One object of the invention is to adapt a Rankine cycle refrigerating system to be operated by a motor having a moderate or low starting torque and drawing a low or moderate starting current from the supply mains. Another object is to reduce the high side pressure when such a system shuts down. Another object is to effect the above results without impairing the operating characteristics of the system. Other objects will be apparent from the detailed description which follows.

The invention involves the novel principle

of storing all the liquid refrigerant in the low temperature side of the system when the machine shuts down and causing the high temperature side to dry out. With the system so arranged the high side pressure falls substantially to that of the low side when the motor stops and the starting load on the motor is correspondingly relieved.

The accompanying drawing illustrates a preferred form and arrangement of apparatus for practicing my improved process, the single view being a front elevational view with certain parts in section of a self-contained refrigerating outfit for domestic use.

The illustrative embodiment of the invention discloses apparatus forming a refrigerating system operating on the Rankine cycle and associated with a refrigerator or cabinet A having an insulated chamber a for the storage of food or other perishable articles. The apparatus comprises an evaporator element 1 disposed within chamber a, a pump or compressor 2 driven by a suitable prime mover such as electric motor 3 as by a belt 3a and adapted to withdraw vaporized refrigerant from evaporator 1 through a pipe 4 and discharge the same at higher temperature and pressure into a condenser 5 which returns the condensed refrigerant to evaporator 1 through a float-type "expansion valve" or feeder 6. The connection between condenser 5 and feeder 6 includes a liquid trap or seal which may be provided by a U tube 7 of relatively small bore. Evaporator 1 may be of any suitable or desired type and may be arranged to freeze liquid in suitable trays 8 as well as to maintain storage chamber a at the desired low temperature. Evaporator 1 is preferably constructed with a storage chamber 1a to take care of variations in the liquid level of the refrigerant and to prevent the same from passing as liquid into compressor 2. Feeder 6 is disposed at such a height relative to evaporator 1 that the float valve 6a in the feeder operates not from the level of the liq-

- uid in the evaporator 1 but from the level of the liquid in the float chamber 6b of the feeder which is connected to the condenser through the previously mentioned U tube or trap 7.
- 5 Any suitable or desired means (not shown) for automatically starting and stopping the prime mover 3 in response to temperature changes in chamber a or in response to pressure changes in the system or for otherwise 75
- 10 putting the apparatus into or out of operation may be provided.
- It is essential to the operation of my improved process that the condenser and piping be so constructed and arranged that when 15
- 15 the machine is shut down all the liquid will be forced to go into the low temperature zone leaving the warm portion of the high side of the system in a dry condition. Perhaps the easiest way to insure this result is 20
- 20 to place the compressor and condenser above the feeder and evaporator and arrange the connection so that all liquid will drain by gravity into the low temperature zone within 25
- 25 Since the disclosed apparatus operates on the Rankine-cycle it will be apparent that the volatile refrigerant fluid in evaporator 1 is caused to evaporate through the action of compressor 2, the vapor drawn off by the latter being forced at higher temperature and pressure into condenser 5 where heat is removed and the vapor caused to condense, the condensate being fed back into the evaporator through feeding device 6. The present invention 30
- 35 is concerned particularly with the phenomena which occur when the apparatus is shut down, and which involve the process of reducing the pressure on the high side of the system in order to relieve the load on compressor when the system is again put into operation. When the compressor shuts down, all condensate in condenser 5 drains out of the zone of the high temperature, i. e. out of 40
- 45 the apparatus disposed outside of refrigerator cabinet A, into the low temperature zone which is inside cabinet A. The high side system above trap 7 accordingly dries out and all of the liquid refrigerant in the system is brought into thermal intimacy with evaporator 1 with the result that the vaporization 50
- 55 of refrigerant fluid at room temperature, such as occurs in similar outfits as heretofore constructed, is entirely avoided. Moreover, the draining of the condensate into trap 7 raises the liquid level in float valve chamber 6b so that float valve 6a rises from its seat and permits the condensate in trap 7 and in chamber 6b to pass over into evaporator 1, header 1a taking care of the increased amount of liquid 60
- 60 in the evaporator, so that an equalization of pressure occurs between the high and low sides of the system and the pressure on the high side falls substantially to the pressure obtaining on the low side. The normal level 65 of liquid is evaporator 1 when the apparatus
- is in operation is indicated in full lines and the higher liquid level which develops when the apparatus shuts down is indicated by the broken line.
- It will be noted that the surface of the liquid in the U tube forming trap 7, which liquid is kept cold by proximity to the evaporator, may be exposed to warm vapor in the condenser during the running period. This would at first thought seem to cause a considerable loss of efficiency as it might appear that the U tube trap 7 and float chamber 6b would do the condensing and put heat back into refrigerator chamber A. It is found, however, that when the area of liquid in contact with its vapor is small, the liquid may be cooled far below the temperature of the vapor with only a negligible amount of condensation taking place thereon. This principle is utilized by making the U tube of small bore, for example $\frac{1}{16}$ " which, however, is sufficiently large to quickly pass any normal supply of liquid reaching it from the condenser. The area of cold liquid at the end of the U tube facing the condenser is thus too small to have any effect during the normal operation of the system and the vapor pressure at its surface falls when the condenser is no longer functioning, as during the shut down periods. It is obvious that little, if any, actual loss of efficiency occurs through the draining of the relatively warm liquid out of the high side into the evaporator after the machine stops since the liquid eventually must go through this step of the cycle. 100
- The form of apparatus herein shown and described is merely for the purpose of illustrating the invention and it will be obvious to those skilled in the art that the invention is capable of varied forms and adaptions. It is, accordingly, to be understood that the invention is not limited to the specific details shown, but covers all changes, modifications, adaptations and variations within the scope of the appended claims. 105
- I claim as my invention:
1. In combination, a cabinet, and refrigerating apparatus of the closed cycle type operating on the Rankine cycle associated with said cabinet, said apparatus being so constructed and arranged that all liquid refrigerant is moved into and stored within said cabinet during the shut down periods of said apparatus, and means restricting the area of contact between the liquid and vapor phases of the refrigerant. 110
2. In combination, a refrigerator cabinet, apparatus of the closed cycle type operating on the Rankine cycle associated with said cabinet including an evaporator within said cabinet and a compressor and a condenser outside said cabinet, said compressor and said condenser being so disposed relative to said evaporator that all liquid refrigerant in the same moves into said cabinet during shut 115
- 120
- 125
- 130

down periods, and a conduit of restricted size establishing a limited area of contact between the liquid and vapor phases of the refrigerant.

5. 3. Refrigerating apparatus operating on the Rankine cycle comprising a compressor, a condenser, a feeding device, and an evaporator connected together to form a closed cycle system, and means intermediate said condenser and said evaporator for moving all condensate into thermal intimacy with said evaporation when said compressor is not operating including a conduit providing a restriction at the point of contact of the liquid and vapor phases of the refrigerant.

4. Refrigerating apparatus of the closed cycle type operating on the Rankine cycle comprising an evaporator, a compressor, a condenser, a liquid feeding device between said condenser and said evaporator, and a liquid trap between said device and said condenser, said device and trap being in thermal intimacy with said evaporator.

5. Refrigerating apparatus of the closed cycle type operating on the Rankine cycle comprising an evaporator, a compressor, a condenser, a liquid feeding device between said condenser and said evaporator, and means forming a trap for liquid between said device and said condenser, said means presenting a restricted surface area of liquid to said condenser.

6. Refrigerating apparatus of the closed cycle type operating on the Rankine cycle comprising an evaporator, a compressor, a condenser, a liquid feeding device for said evaporator, and a U tube of small bore between said device and said condenser and forming a trap for liquid.

40. 7. In combination, a refrigerator cabinet, apparatus of the closed cycle type operating on the Rankine cycle associated with said cabinet including an evaporator within said cabinet and a compressor and a condenser outside said cabinet, said condenser being so disposed relative to said evaporator that condensate in the former will move by gravity toward the latter, and means permitting all the condensate to pass into said refrigerator cabinet 45 when the apparatus is shut down and reducing to a minimum the area of contact between the liquid and vapor phases of the refrigerant.

8. In combination, a refrigerator cabinet, apparatus of the closed cycle type operating on the Rankine cycle associated with said cabinet including an evaporator within said cabinet and a compressor and a condenser outside said cabinet, said condenser being so disposed relative to said evaporator that all condensate in the former will move by gravity toward the latter, and a float device controlling the feeding of condensate to said evaporator and permitting movement of the 60 condensate into said evaporator when the

system shuts down, the connection from said condenser to said device forming a trap for liquid.

9. In combination, a refrigerator cabinet, apparatus of the closed cycle type operating on the Rankine cycle associated with said cabinet including an evaporator within said cabinet and a compressor and a condenser outside said cabinet, said condenser being so disposed relative to said evaporator that condensate in the former will move by gravity toward the latter, a float device within said cabinet controlling the feeding of the condensate to said evaporator and permitting movement of the condensate into said evaporator when the system shuts down, and a U tube of restricted bore adjacent said device and forming a liquid trap between the latter and said condenser.

10. A self contained refrigerating outfit comprising a refrigerator and apparatus associated therewith for extracting heat therefrom and arranged for automatic or manual control, said apparatus operating on the Rankine cycle and comprising a compressor and a condenser upon the exterior of the refrigerator and a prime mover for said compressor, within said refrigerator an evaporator and liquid feeding device therefor, said condenser and compressor being so disposed that during shut down periods all liquid refrigerant moves into the parts of the apparatus within the refrigerator, and means establishing a restriction in the connection between said condenser and said device at the point of contact of the liquid and vapor phases of the refrigerant.

11. A self contained refrigerating outfit comprising a refrigerator and apparatus associated therewith for extracting heat therefrom and arranged for automatic or manual control, said apparatus operating on the Rankine cycle and comprising a compressor and a condenser upon the exterior of the refrigerator, a prime mover for said compressor, and within said refrigerator an evaporator and a float feeding device, a liquid trap between said device and said condenser and disposed within said refrigerator, said condenser and compressor being arranged to cause liquid refrigerant to move by gravity into the parts within said refrigerator.

12. A self contained refrigerating outfit comprising a refrigerator and apparatus associated therewith for extracting heat therefrom and arranged for automatic or manual control, said apparatus operating on the Rankine cycle and comprising a compressor and a condenser upon the exterior of the refrigerator, a prime mover for said compressor, and within said refrigerator an evaporator and a float feeding device controlled independently of the liquid level in said evaporator, a U tube of restricted bore within said refrigerator adjacent said de-
